(57) **CLAIM**

The ornamental design for an electric screwdriver, as shown and described.

DESCRIPTION

FIG. 1 is a front, right, top perspective view of an electric screwdriver, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the enlarged scale thereof;

FIG. 8 is a bottom plan view of the enlarged scale thereof;

FIG. 9 is an enlarged view of detail 9 in FIG. 1;

FIG. 10 is a front, right, top perspective view of its reduced scale in a detached state;

FIG. 11 is a rear, left, bottom perspective view of its reduced scale in a detached state;

FIG. 12 is a front elevational view of its reduced scale in a detached state;

FIG. 13 is a left side view of its reduced scale in a detached state;

FIG. 14 is an enlarged view of detail 14 in FIG. 10;

FIG. 15 is an enlarged view of detail 15 in FIG. 10;

FIG. 16 is an enlarged view of detail 16 in FIG. 10;

FIG. 17 is an enlarged view of detail 17 in FIG. 11;

FIG. 18 is an enlarged view of detail 18 in FIG. 11;

FIG. 19 is an enlarged view of detail 19 in FIG. 12;

FIG. 20 is an enlarged view of detail 20 in FIG. 12;

FIG. 21 is an enlarged view of detail 21 in FIG. 13; and,

FIG. 22 is an enlarged view of detail 22 in FIG. 13.

The dashed broken lines in the figures are for the purposes of illustrating portions of the electric screwdriver and form no part of the claimed design.

The dash-dot-dash broken lines are for notating enlarged views and form no part of the claimed design.

1 Claim, 21 Drawing Sheets
